United States Patent Office.

JOSHUA MONROE, OF NEW YORK, N. Y.

Letters Patent No. 86,856, dated February 9, 1869.

IMPROVEMENT IN VELOCIPEDES.

The Schedule referred to in these Letters Patent and making part of the same.

To all whom it may concern:

Be it known that I, JOSHUA MONROE, of the city, county, and State of New York, have invented certain new and useful Improvements in Velocipedes; and I do hereby declare the following to be a full, clear, and exact description of the same, reference being had to the accompanying drawings, which are made a part of this specification.

The subject of this invention is a velocipede, in which the following useful features of novelty are embodied, to wit:

The saddle or seat for the person propelling the instrument may be shifted in a forward or backward direction, and held in any desired position to adapt the distance between the propelling-cranks and seat to the length of the limbs of such person; a seat is provided for a person or persons, who may ride at ease and without exertion; the last-mentioned seat is provided with springs, to conduce to the comfort of the occupant; the vertical spindle of the propelling-wheel has an elastic bearing above said wheel, whereby the latter is allowed to yield in overriding obstacles; a rock-lever, operated by the hands, is employed, to propel, or assist in propelling, as well as to guide the velocipede; pins projecting from the bearing-frame of the propelling-wheel serve as foot-rests, to be used when the propelling is effected by the hands alone; and stirrups, to be strapped to the feet, enable the latter to be effectively applied to the arms of the propelling-wheels.

Figure 1 is a sectional side elevation of a velocipede, illustrating my invention.

Figure 2 is a front elevation of the front part of the same.

Figures 3 and 4 are views of the attachments for the feet.

Similar letters of reference indicate corresponding parts in the different figures.

A represents the reach or main longitudinal connecting-bar, from the upright forward part of which project rigidly the lugs *a a'*, which form bearings or collars for the upright spindle B of the propelling-wheel C.

The rear end of the reach is secured to a bolster, and forms, in conjunction with the latter, a base or support for the seat E, which surmounts a two-wheeled axle, F, so that a person, occupying said seat E, may ride without taking part in the propelling-operation.

Springs G are suitably retained between the axle and bolster, and permit the seat to yield, in order that the occupant may not be subjected to undue shocks.

The saddle or seat H, for the one who propels, is adjustable longitudinally upon the reach, so as to occupy a position nearer to or further from the points where the feet are applied to the propelling-mechanism, and thus adapt the velocipede to the length of the limbs of the person performing the propelling-operation.

For the last-mentioned purpose, the reach may be slotted, as at *h*, to receive and permit the backward-and-forward motion of the bolt which attaches seat H to the reach.

The driving-wheel C has its bearings in the bent.

two-limbed bar I, which depends rigidly from the spindle B.

Pinion-wheels *m m* are made fast to the outer extremities of the journals of wheel C, and with these pinions mesh cog-wheels *m' m'*, whose journals project outward and horizontally from diametrically-opposite points of the bearing-bar I.

Elongated wrist-pins project from the cog-wheels *m' m'*, and are loosely encircled by the tubes or sleeves *n n*, to which the feet are applied to propel the velocipede.

Pins *o o*, projecting outward from bar I, serve as foot-rests.

To enable the feet of the person sitting upon the seat H to be more effectively applied to and kept upon the sleeves *n*, of the propelling-arms or wrist-pins, I provide for the feet semi-tubular attachments J, figs. 3 and 4, which are to be strapped upon the feet, and which are adapted to rest upon and partially embrace the tubes *n n*, so as to keep the feet steadily in position thereon.

To the wrist-pins are attached pitman-rods L [L], which are pivoted at their upper ends to the arms of a rock-lever or handle, M, which has pivotal attachment, at *m' m'*, to arms projecting rigidly from a fixed collar, N, upon the spindle B.

A spiral spring, P, encircling the spindle B, and situated between collar N and lug *a*, permits the driving-wheel and spindle to yield in an upward direction, so as to avoid hard shocks in passing over prominences and obstacles.

A shoulder, *b*, is formed on the spindle above the lug *a*.

It will be observed that the driving-wheel C may be turned, and the velocipede propelled by the feet, as applied to the arms at *n*, or by the hands, as applied to the rock-lever M; also, that the hands and feet may be brought into requisition simultaneously, as well as separately, both in driving and guiding.

Having thus described my invention,

What I claim as new, and desire to secure by Letters Patent, is—

1. The steering and propelling-lever M, in combination with pitman-rods L, geared wheels *m m'*, propelling-wheel C, perch A, and wheels G, substantially as and for the purpose described.

2. The arrangement with the above of the spring P, applied and operating as described.

3. The combination of the adjustable seat H and stationary seat E with perch A, substantially as and for the purpose described.

4. The pins or arms *o o*, constituting stationary foot-rests, as explained.

5. Combination of slotted bracket *a a'* with perch A, by means of which the height of the perch can be adjusted.

JOSHUA MONROE.
